Specification for Design.

Patented Oct. 5, 1920.

Application filed May 15, 1920. Serial No. 381,754. Term of patent 3½ years.

To all whom it may concern:

Be it known that I, ALEXANDER G. ZOGRAPHOS, a citizen of the United States, residing at New York, in the county of New York and State of New York, have invented a new, original, and ornamental Design for Lace, of which the following is a specification, reference being had to the accompanying drawing, forming part thereof.

The figure is a plan view of the lace, showing my new design.

I claim:-

The ornamental design for lace, as shown.

ALEXANDER G. ZOGRAPHOS.
